UNITED STATES PATENT OFFICE.

JEANE D. GUNDER, OF CHICAGO, ILLINOIS, ASSIGNOR TO THE J. A. POZZONI PHARMACAL COMPANY, OF CHICAGO, ILLINOIS, A CORPORATION OF ILLINOIS.

DESIGN FOR A PUFF-BOX.

42,749.

Specification for Design.

Patented July 9, 1912.

Application filed April 19, 1912. Serial No. 691,955. Term of patent 14 years.

To all whom it may concern:

Be it known that I, JEANE D. GUNDER, a citizen of the United States, residing at Chicago, in the county of Cook and State of Illinois, have invented a new, original, and ornamental Design for a Puff-Box, of which the following is a specification, reference being had to the accompanying drawing, forming a part thereof.

The ornamental design consists in the oval shape of the box as shown particularly at

Fig. 2, with the bilge 10 in the body, with the raised or cameo scroll design formed upon such bilge, together with the oval panel in the cover surrounded by the bulged ornamental border of scroll work also in cameo, and all surrounded by the milled edge of the cover indicated at 11.

I claim—

The ornamental design for puff box as shown and described.

JEANE D. GUNDER.
